ELECTRICAL CONNECTER

Filed May 26, 1936

UNITED STATES PATENT OFFICE

2,143,131

ELECTRICAL CONNECTER

Henry E. Piltz, Greenwood Township, Oceana County, Mich.

Application May 26, 1936, Serial No. 81,948

2 Claims. (Cl. 173—361)

My invention relates broadly to electrical connectors and more particularly to an improved construction of separable plug connector.

One of the objects of my invention is to provide a two part plug connector in which the coacting parts may be very readily assembled or disassembled in establishing the electrical connection.

Another object of my invention is to provide a construction of two part plug connector in which a single projecting member may be readily centered and inserted in the coacting part of the plug connector for establishing a quick detachable connection.

Still another object of my invention is to provide a construction of two part electrical connector in which twisting or tangling of the conductors extending to the coacting parts of the two part plug is avoided.

A further object of my invention is to provide a construction of two part connector in which the coacting parts may be interconnected by movement of the parts in cooperative relation from any convenient position about the coacting parts without limitation.

A still further object of my invention is to provide a two part connector which may be readily assembled without any particular skill or knowledge of the device and with nothing more than a knife or screw driver as a tool.

Still another object of my invention is to provide a construction of plug adapted to be engaged in the ordinary screw receptacle and wherein the plug does not require the formation of screw threads on the sides thereof.

A further object of my invention is to provide a construction of separable plug adapted to engage the screw threads of an ordinary socket and in which the plug is formed from a cylindrical wall structure through which a selected number of rivet members and a resilient connecting device extend in predetermined spaced relation for providing guide means for facilitating the insertion or removal of the plug in the screw-threaded receptacle.

A still further object of my invention is to provide a construction of screw-threaded separable plug adaptor having a central recess therein for receiving a single projecting member carrying electrical contactors therein operative to establish electrical connection with contacts in the removable plug.

Other and further objects of my invention reside in the construction of separable plug connector as set forth more fully in the specification

hereinafter following by reference to the accompanying drawing, in which:

Figure 1 is a side elevational view showing the parts of the electrical connector of my invention in aligned position ready to be interfitted to establish an electrical connection; Fig. 2 is a longitudinal sectional view through the electrical connector of my invention; Fig. 3 is a lateral cross-sectional view on line 3—3 of Fig. 2; Fig. 4 is a cross-sectional view of the screw-threaded plug employed in the electrical connector of my invention; Fig. 5 is a longitudinal cross-sectional view of a modified form of electrical connector embodying my invention; Fig. 6 is an elevational view with parts broken away and illustrated in cross-section taken at right angles to the view shown in Fig. 5; and Fig. 7 is a lateral cross-sectional view taken on line 7—7 of Fig. 5.

My invention is directed to a construction of two part separable connector which is inexpensive in manufacture and simple in its construction. The connector of my invention is a radical departure from connectors heretofore known in that I provide a construction wherein it is unnecessary to prod and feel for the proper apertures in a plug receptacle for inserting the projecting prongs of the usual type separable connector. The inconvenience encountered in attempting to insert a two prong plug into a wall type receptacle where the conditions are such that the receptacle cannot be readily seen is a frequent occurrence. It is often necessary to make several attempts to push the two prong plug into engagement with the apertures in the wall type receptacle in various angular positions without success. Moreover, it is a common occurrence for the prongs to bend out of alignment and make it impossible to establish an interengagement with the wall receptacle. The fact that such separable plugs tend to draw apart is also a very great disadvantage.

In the separable plug of my invention, I provide a single projecting member of circular cross-section which carries contactors serving both sides of the high potential line and adapted to be inserted in a central recess in a separable plug member. Suitable insulation is provided for the contactors carried by the projecting member and connection is established between the said contactors and contacts within the separable plug. The contacts within the separable plug are so arranged that a locking interengagement is established with the contacts carried by the projecting member so that the projecting member cannot be accidentally withdrawn from the recess in the separable plug but can only be withdrawn

by applying a positive force to the projecting member. I construct the coacting separable plug without the necessity of providing screw threads on the exterior wall of the separable plugs ordinarily required. I accomplish this by mounting metallic members laterally in the wall of the separable plug coacting with a resilient electrically conducting member to engage the screw threads of a receptacle into which the separable plug is inserted for forming both a rigid mechanical connection and a good electrical connection therewith. The separable plug connector of my invention is constructed from a minimum number of parts. The portions of the separable plug which are formed from insulation material may be readily molded from phenol condensation products and other moldable insulation materials. The molded parts of the separable plug require no machine work. The electrical connecting parts are either die stamped or are formed by screw machine operations. For the purpose of illustrating my invention, I have shown the projectible plug portion of my invention coacting with a screw plug which may be adapted to any form of screw-threaded receptacle. However, I desire that it be clearly understood that the projectible portion of the connector of my invention may be used in cooperation with a baseboard receptacle, a junction box, an outlet box, or various forms of terminal boxes having a built-in contacting device equivalent to the connecting device shown herein and which coacts with the projecting plug. Moreover, my improved construction of projecting plug which I have illustrated is adaptable as a connection for electric irons and other forms of electrical appliances.

Referring to the drawing in detail, reference character 1 designates a screw plug which coacts with the insertable projecting plug 2. A protective housing 3 is provided for the insertable projecting plug 2 and through which the conducting wires 4 pass. The screw plug 1 is provided with an annular flange 5 facilitating the insertion of the screw plug into a screw-threaded receptacle of any kind. The screw plug 1 contains a central bore 6 provided with a chamfered entrance 7 which facilitates the location and centering of the insertable projecting plug in the screw plug. The screw plug 1 is molded in suitable form and in order to simplify the molding process, the plug is molded with a smooth cylindrical wall having a molded base 8. A center contact 9 having a pin 12 extending therefrom is molded directly in the end of the screw plug 1. The center pin 12 extends axially through bore 6 for substantially one-half a depth thereof and is firmly anchored in the molded plug 1 by reason of the knurling 14 which serves as a grip between the molded material of plug 1 and the pin 12. The upper extremity of pin 12 is chamfered as represented at 12a to facilitate insertion of the telescopic contacting member 24 forming part of the insertable projecting plug 2.

The screw plug 1 has a sleeve member 15 extending laterally through one wall thereof. Sleeve member 15 serves to house the contacting ball 16 and a spring 17 tending to continuously urge contacting ball 16 radially inwardly. The inner end of sleeve 15 which opens into bore 6 is restricted to allow contacting ball 16 to partially project into the bore 6 as illustrated in Fig. 4. Contacting ball 16 is engaged by the outer sleeve 23 of the insertable projecting plug 2. The contacting ball 16 is yieldably supported by spring 17 and provides a conductive electrical connection

to the outstruck end 18 of sleeve 15 forming a thread engaging means for the threaded wall 19 of the screw-threaded receptacle 20. The receptacle 20 is of standard construction and merely a fragmentary portion thereof has been illustrated for purposes of explaining my invention. 5

The plug 1 is molded with a pair of headed radially disposed rivets directly molded into the wall of the plug and arranged in spaced relation equal to the distance between adjacent threads 10 in the threaded wall 19 of receptacle 20. The headed rivets 21 and 22 extend partially into the wall of plug 1 and are spaced on either side of an axis passing through the outstruck end 18 of sleeve 15 to assimilate screw threads. That is 15 to say, the headed ends of rivets 21 and 22 are so arranged with respect to the outstruck end 18 of sleeve 15 that they mutually coact in a spiral path circumferentially of plug 1 to engage the internal screw threads 19 in receptacle 20. It 20 will be clear that this construction is very simple and inexpensive and avoids the necessity of providing the usual screw-threaded shell surrounding the plug for coaction with internal screw threads on receptacle 20. 25

The insertable projecting plug 2 comprises concentrically arranged outer sleeve 23 and inner sleeve 24 spaced by an insulation sleeve 25. A tongue or lug 26 is integrally connected with sleeve 23 and projects therefrom providing a supporting means for binding screw 27 around which one of the conductors of the conducting wires 4 is secured. A tongue or lug 28 integrally connected with inner sleeve 24 projects from inner sleeve 24 and provides a mounting means for 30 binding screw 29 under which the other conductor of the conducting wires 4 is secured. The projecting plug 2 is mounted in a disc 30 which is screw-threaded on its periphery as indicated at 31. The screw threads 31 on disc 30 serve to 40 engage internal screw threads formed interiorly of protective housing 3 as illustrated in Fig. 2. This arrangement permits the protective housing 3 to be initially separated from disc 30 for allowing electrical connection to be made be- 45 tween the ends of conducting wires 4 and binding screws 27 and 29. Thereafter, the protective housing 3 may be rigidly connected with insertable plug 2 by the engagement of external screw threads 31 on disc 30 with internal screw threads 50 within protective housing 3.

I may provide other methods of mounting the insertable plug 2 with respect to the protective housing and for purposes of explaining my one modified form of my invention, I have illustrated 55 in Figs. 5, 6 and 7 a form of protective housing indicated at 33 in which I provide oppositely disposed complementary eccentrically arranged internal grooves 34 and 35 with slots 36 and 37 diametrically arranged opposite each other and 60 between the respective ends of the complementary eccentrically arranged internal grooves 34 and 35. The slots 36 and 37 provide entrances for diametrically arranged lug extensions 38 and 40 integrally connected with outer sleeve 23 and inner sleeve 24 respectively. The arrangement of the lug extensions is illustrated in Fig. 5 where it will be seen that lug 38 is bent normal to the axis of sleeve 23 and forms an engaging means 70 adapted to pass through slot 36 and engage eccentric groove 34. Lug 38 extends upwardly and carries binding screw 39 serving as a connector for one of the conductors of the conducting wires 4. The lug 40 which extends from the inner 75

sleeve 24 is offset to allow the insertion of an insulated gasket 42 beneath lug extension 40 for preventing short-circuiting between inner sleeve 24 and outer sleeve 23. Lug 40 serves as an engaging means in coaction with eccentric groove 35 as lug 40 passes through slot 31. The binding screw 41 carried by lug extension 40 serves as an attachment means for the other conductor of the conducting wires 4. The concentrically arranged sleeves provide a rigid assembly with respect to which the diametrically extending lugs serve as supporting means when engaged beneath the protective housing 3. The headed members 21 and 22 may merely pass through a portion of the wall 22 of the plug 1 and may be molded therein. The important consideration is that headed members 21 and 22 be so spaced with respect to each other and with respect to the projection 18 of sleeve 15 that the pitch of the imaginary thread thus provided by a spiral line extending around the circumference of plug 1 and passing successively through headed member 21, projection 18, and headed member 22, corresponds to the pitch of the coacting screw-threaded receptacle into which the plug must be inserted or removed. I may arrange the supporting and connecting lugs in a variety of ways with respect to the telescopically disposed sleeves and the constructions I have illustrated herein are intended merely as illustrative of the principles of my invention.

While I have described my invention in certain preferred embodiments, I realize that modifications may be made and that no limitations upon

my invention are intended other than may be imposed by the scope of the appended claims.

What I claim as new and desire to secure by Letters Patent of the United States is as follows:

1. An electrical plug connector comprising a rigid contact assembly including a pair of concentrically arranged conductive sleeves insulated from each other, lugs extending from adjacent ends of said sleeves, means for establishing electrical connection with each of said lugs adjacent the extremities thereof, and a detachable protective housing for substantially enclosing said lugs; said lugs being bent normal to the axis of said sleeves in opposite directions and double bent upon themselves to provide oppositely extending arms engageable with said housing and having the extremities thereof extending interiorly of said housing.

2. An electrical plug connector as set forth in claim 1 and wherein said housing is provided with an inner circumferential groove having semi-circular oppositely disposed sections arranged off-center and engageable by said oppositely extending arms, said arms being clamped between diametrically opposite points in the respective sections of said groove and said groove having exit slots at the portions of greatest diametrical spacing, said arms being displaceable in the respective sections of said groove toward said slots for detaching said housing and providing access to said means for establishing electrical connection to said lugs.
